UNITED STATES PATENT OFFICE

2,459,944

CENTRIFUGAL SEPARATOR

Leo D. Jones and Hugh S. Barnaby, Philadelphia, Pa., assignors to The Sharples Corporation, Philadelphia, Pa., a corporation of Delaware

Application October 1, 1943, Serial No. 504,562

3 Claims. (Cl. 183—77)

1

The present invention pertains to a system and a machine for separating non-gaseous impurities from a gas. It was conceived in connection with research having for its object the separation of solid impurities from a gas, and will accordingly be described in connection with that problem.

A feature of the invention consists in the fact that it provides a machine and system which improve the efficiency and economy of separation of solids from gases by providing a centrifugal rotor capable of removing solid impurities of even very small size during passage of the gas under treatment through the centrifugal rotor at high capacity.

Another feature of the invention consists in the fact that it involves use of a centrifugal rotor in which the gas to be purified is brought up to the speed of centrifugation by accelerating vanes, and then subjected to centrifugation in a zone provided with a plurality of discs having vanes which retain the gas at the speed of rotation of the rotor during passage through the zones of centrifugation between the successive discs, the impelling force by which the gas under purification is fed to and through the centrifugal rotor being derived from means forming no part of the centrifugal rotor; e. g., by an exhauster in a conduit receiving the gas from the rotor, or a blower in a conduit through which the gas is fed to the rotor.

By employing vanes for bringing the gas up to the speed of the rotor, and providing vanes between the discs and in the space through which the gas is discharged from the rotor, we are able to maintain the rotational velocity of the gas substantially constant during the time it is subjected to centrifugal force in the rotor, thereby minimizing turbulence and promoting the efficiency of separation.

Another feature of the invention consists in the fact that the internal space into which the gas is discharged after being subjected to centrifugation between the successive discs is of variable cross section, this cross section increasing in the direction of discharge of the gas from the rotor. By providing a progressively increasing gas space within the circumferences of the respective discs as the gas flows toward the discharge end of the rotor, more space is provided to receive the gas inwardly from the respective discs progressively as the amount of gas to be accommodated increases, with the result that uniform division of the parallel streams of gas among the spaces between the respective discs is promoted.

Still further features and advantages of the invention will be evident from a reading of the following specification in the light of the attached drawing, in which,

2

Figure 1 is a diagrammatic illustration of a system embodying the centrifugal separator of the invention.

Figure 2 is a longitudinal cross section through a centrifugal separator embodying the features of the invention.

Figure 3 is a cross section on the line 3—3 of Figure 2, and

Figure 4 is a cross section on the line 4—4 of Figure 2.

Referring to the drawing by reference characters, Figure 1 illustrates the general principle of operation of the invention. As there illustrated, the gas to be purified is sucked, together with solid impurities, from a source through centrifugal separator 10 by any suitable impelling force, such as provided by the impeller 11. Solids are separated from the gas in centrifugal separator 10 and separately discharged, while purified gas is discharged by the impeller. The impeller 11 may be a suitable pump, or it may be any other mechanism capable of applying suction to suck a mixture of gas and solids into the centrifugal separator 10 and to suck the purified gas from that centrifugal separator; e. g., it may be an internal combustion engine, and the centrifugal separator 10 may be designed to effect separation of solids, such as dirt, from air sucked through the centrifugal rotor to the internal combustion engine for use therein.

Alternatively, a blower may be provided to blow the mixture of gas and solids through the centrifugal separator 10. An important aspect of the invention consists in the fact that it involves use of a centrifugal separator which has substantially no pumping effect of its own, the impelling force for feed of gas through the centrifugal separator to be purified being derived entirely from a controllable external impeller.

The centrifugal separator of the invention is illustrated in Figures 2, 3 and 4 of the drawing. In describing this centrifugal separator, we shall assume for the purpose of convenience of description that it is mounted on a vertical axis as illustrated in Figure 2 of the drawing. In considering this machine, however, it should be realized that it may be mounted on a horizontal axis or an axis located in any plane, or that the position of parts may be upside down with respect to that illustrated in Figure 2. The centrifugal separator comprises an external casing 12 in which is mounted a rotor 13 driven by a shaft 14 from a motor 35. The casing 12 is provided with an inlet 15 at the upper end of its upper frusto-conical section 16 for receiving the gas to be purified, this inlet 15 being connected in a gas-tight fashion to any suitable conduit connected with a source of the gas. The upper frusto-conical section 16 of the casing is connected by bolts 17 to the central section 18, which

is in turn connected to the lower casing section 18, supporting the motor 35, by bolts 20.

A plurality of stationary vanes 21 (see Figure 3) are provided in the inlet section of the casing, and these vanes are curved as indicated at 36 (see Figure 3) to impart an initial movement of rotation to the gas as it enters the centrifugal rotor. The upper end of the centrifugal rotor consists of a feed section 22 comprising a lower frusto-conical wall 23 and an upper frusto-conical wall 24 interconnected by vanes 25. These vanes 25 are curved forwardly in the direction of rotation of the rotor at their upper ends, as indicated at 37 in Figure 3, in order to accelerate the gas more smoothly to the speed of the rotor.

The feed section 22 of the rotor serves to bring the gas up to the speed of the rotor and to deliver it into the annular portion of the rotor lying within the circumferential wall 26 thereof, and the gas flows from this space into the space between successive discs 28 of a rotating disc nest 27. The discs 28 are of frusto-conical shape and a plurality of vanes 29, which preferably extend substantially radially between successive discs, serve to maintain the rotation of the gas under treatment at substantially the speed of rotation of the rotor during passage thereof inwardly through the space between successive discs.

An axially extending frusto-conical spacer 30 surrounds the shaft 14 at the longitudinal portion of said shaft within the inner circumferences of the discs, and this spacer is provided with a plurality of radially and axially extending webs 31 which serve as vanes to maintain the gas discharged inwardly from the space between the discs 28 at the rate of rotation of the rotor, and the outer edges 32 of the webs 31 enter notches in the inner portions of the respective discs, and thus effect securement and location of the discs for rotation with the rotor.

It will be seen that the cross section of the space 38 between the outer circumference of the spacer cone 30 and the inner circumferences of the discs 28 becomes progressively larger from the zone within the uppermost pair of discs downwardly to the zone of discharge of gas through the inner circumference 39 of the lower end 33 of the centrifugal rotor. By reason of this arrangement, a progressively larger space is provided to receive the gas as progressively more gas flows into this central space from the spaces between respective pairs of discs. By provision of this larger space, excessive resistance to flow of gases through spaces between the lower discs of the disc nest is avoided, and uniform division of the parallel streams of gas between respective discs of the disc nest is promoted.

Upon being discharged from the lower end of the rotor through the space between the outer circumference 40 of the spacer 30 and the inner circumference 39 of the lower wall of the rotor, this gas flows into an annular passageway 41 through which it passes spirally into an outlet conduit 42, which may communicate with any suitable impeller for drawing gas through the centrifugal rotor, as illustrated at 11 in Figure 1 of the drawing.

Solid impurities with some gas are separated from the gas during passage thereof through the parallel paths between successive discs 28 and projected outwardly along the lower faces of these respective discs under the influence of centrifugal force against a circumferential wall 26, which is provided with a number of indentations forming

pockets 43 provided with outlets 44 through which the solid impurities and associated gas are continuously discharged from the rotor. At the time these solid impurities and gas are discharged from the outlets 44, they have a high tangential velocity, and this tangential velocity carries them circumferentially around the inner wall of the central section 18 of the casing 12 until they reach a vertical longitudinal slot 45 (Figure 4) in that wall, which extends longitudinally of the wall along the entire length thereof surrounding the discharge outlets 44, the solids and gas being discharged through the slot 45 into a discharge conduit 46, which is tapered from the height and width of slot 45 to a circular section, as illustrated in Figures 2 and 4. A plurality of slots 45 and discharge conduits 46 may be provided around the circumferential wall 18 if desired, although satisfactory operation has been attained by use of only a single such discharge zone.

It will be seen that the wall 26 substantially isolates the space within the rotor surrounding the discs 28 from the atmosphere surrounding the rotor within the central section 18 of the casing, the only communication between these two spaces being through the small discharge outlets 44. By reason of this substantial isolation of the space within the rotor surrounding the discs, turbulence in this zone is minimized, and efficient separation is promoted. If, instead of providing a circumferential wall 26 having perforations of small size, the circumferential wall 26 were to be omitted, and the solids discharged directly through the slot 45 and outlet conduit 46 from the rotating discs, great turbulence would be caused within the space surrounding the discs, with the result that the separation and discharge of the solid impurities would be a very inefficient operation. This difficulty is avoided in the construction of the present invention by providing a circumferential wall rotating with the discs and having outlets of small size, and effecting continuous discharge of the solids from the casing under the inertia of their discharge through said outlets.

The rotor, driving connections and relative arrangement of adjacent parts of the rotor and surrounding casing are constructed in such a manner as to enable the rotor to be driven at very high speed with a minimum of vibration and a minimum of leakage between the respective parts. The upper end of the motor shaft drives a coupling member 47 which, in normal operation of the machine, is connected through a pin 48 to a slot on the lower end 49 of the rotor shaft 14. The bottom section 19 of the rotor casing 12 is extended conically upwardly and inwardly at its lower end as indicated at 50 and the retainer 51 for the lower bearing 52 of the shaft 14 is secured to the underside of this extension 50. The lower bearing 52 also serves to provide indirect bearing support as the top bearing for the shaft of the motor 35.

The upper end 53 of the shaft 14 is mounted for rotation within a bearing 54 which may be secured to the shaft by a nut 55, and which is mounted within the annular cylindrical central portion 56 of a stationary central retaining member 57 which is closed at its central part and provides an upper surface extending in line with the upper surface of the inner frusto-conical wall 23 of the feed section 22. The central retaining member 57 is secured to, or formed integrally with, the upper frusto-conical section 16 of the casing 12, and may conveniently be inter-connected with this member 16 through the vanes or

webs 21 which serve to assist in bringing the gas up to speed as it is introduced into the centrifugal rotor. The feed section 22 of the rotor is secured to the frusto-conical spacer 30 by bolts 58, and the shaft 14 is keyed to the spacer 30 as indicated at 59. The lower end of the spacer 30 is provided with a flange 60 extending outwardly from a web formed at the under end of the spacer, and this flange 60 constitutes the inner portion of the bottom 33 of the rotor, being secured to an intermediate section 61 which is in turn secured to the circumferential wall 26 of the rotor.

It will be seen that the shaft 14 drives the cone 30 through the keyed connection 59 and that this results in driving all of the rotor parts, including the discs 28, at the speed of the shaft. It will also be seen that, when the bolts 58 are secured in position against the upper side of the inner frusto-conical wall 23 of the feed section 22, this securing, acting through the respective vanes 29 and discs 27, serves to clamp the entire disc assembly tightly in the position illustrated in the drawing.

From the above discussion, it will be seen that the rotor and all associated parts may be removed from the casing by merely removing the upper, frusto-conical section 16 and nut 55 and lifting the rotor from the shaft 14, upwardly from the casing and from shaft 14. The motor 35 is secured to the bottom section 19 of the casing 12 by bolts 62, and this motor may be removed from its association with the centrifugal separator by removal of these bolts 62.

The disc nest and feed section of the rotor may be separately removed from the rotor for cleaning or any other purpose, after removal of the section 16 of the casing 12 and nut 55, merely by removal of the bolts 58, and lifting of the feed section and then the discs from their association with the remaining rotor parts.

It will be seen from the above discussion that the machine of the invention provides bearing and driving connections by which the rotor may be driven at high speed with a minimum of vibration. The relatively rigid mounting of the rotor driving and bearing connections enables us to provide relatively moving parts with very small clearances, and thus minimizes the dangers and disadvantages which would be caused by substantial leakage. Thus, the clearances 63, 64, 65, 66, etc. between rotor parts and stationary casing parts may be very small with the driving and bearing connections described above.

An important factor in prevention of undesirable leakage also results from the provision of special sealing arrangements and impellers. Thus, by providing the inter-connecting vanes 25 in the feed section 22 of the rotor extending upwardly to a portion of the feed section adjacent the clearance 63, gas is subjected to a very positive impelling effect in this zone which causes flow thereof through the feed section 22 into the main body of the rotor. Insofar as there is any flow whatever of gases through the clearance 63, this flow is a flow outwardly through the clearance 63 into the feed zone, rather than the reverse. As a result of this provision of means for positively impelling gases outwardly through the clearance 63 toward the main body of the rotor the difficulty which would be encountered if the impure gases were to leak into the bearing space is avoided.

Even more important than the features discussed above for avoidance of leakage of impure air into the bearing space is the construction

by which leakage of dirt or impure air from the space surrounding the rotor into the discharged gas is avoided. If impure gas or dirt were to leak into the purified gas as it is discharged from the space 38 into the stationary discharge passageway 41, this would, of course, offset to a large extent the advantages attained in the previous purification of this discharged gas. A close-clearance labyrinth seal is provided between the innermost portion 60 of the bottom of the rotor and an upwardly projecting portion 61 of the bottom section 19 of the casing, as indicated at 68. In view of the importance of avoiding flow of air containing impurities inwardly through this space from the space surrounding the rotor, however, we also provide impelling blades 69 and 70 designed to create an outward flow of air through the space adjacent the bottom of the rotor. Thus, in order to obviate all possibility of inward flow of air and/or dirt through this zone, we provide impellers which cause flow of air outwardly.

The provision of the vanes 25 in the feed zone and the absence of such vanes in the space between the inner circumference of the frusto-conical section 16 of the casing and the outer surface of the frusto-conical wall 24 of the feed section causes suction of gas inwardly through the space 64 of the wall 24 and the overlying surface of the section 16 of the casing. This suction reduces the pressure in the space surrounding the wall 26, and this reduction of pressure around the wall 26 facilitates the sealing effect of the impellers 69 and 70 and labyrinth seal 68 in sealing the zone of discharge of gas from the rotor from contamination by gas and solids from the space surrounding the rotor.

When the rotor is driven at the high speeds for which it is designed, the pressure in the space surrounding the wall 26 is lower than that in the air spaces of the pockets 43, with the result that a mixture of the gas under treatment and of impurities is continuously discharged through the outlets 44. This lowered pressure in the space surrounding the wall 26 as compared to the pressure within the rotor is also facilitated by the effect of the impeller vanes 25, as discussed above.

It will be evident from the above description that air entering the inlet 15 is first given a slight rotational impulse in the direction of rotor rotation by the curved lower edges of the stationary vanes 21, and that it is thereafter brought up to rotor speed by the vanes 25 in the feed section of the rotor, and passed from the feed section into the main body of the rotor at a speed of rotation approximating that of the rotor itself. From this zone, the gas is purified during its flow inwardly through parallel paths between the discs 28, and is thence discharged from the rotor through the passage 41 in the bottom section 19 of the casing and the conduit 42. The vanes 25 of the feed section 22 of the rotor act as impeller blades to cause flow of gas into the space surrounding the discs 28, but this impelling effect is counteracted by the reverse impelling effect of the vanes 29 between the respective discs 28. By reason of this counter-acting effect, and the resistance to flow of the various elements of the centrifugal and casing, there is practically no tendency for gas to flow through the centrifugal unless an impeller of some kind is connected to the inlet or outlet conduits to induce such flow.

This provision of a machine which has virtually no

impelling effect of its own, when combined in a system providing the necessary impeller, enables the operator to pass the gas to be purified through the centrifugal rotor at a rate best adapted to secure adequate purification of the gas, since the gas may be passed through the rotor at a low rate in cases in which it is difficult to purify or in which extremely fine purification is desired, or it may be passed at a high rate in cases in which the gas is relatively easy to purify or only relatively coarse or heavy impurities are to be removed.

Since various other modifications are possible, we do not wish to be limited except by the scope of the following claims.

We claim:

1. In a centrifugal separator for separating non-gaseous impurities from a gas, the combination comprising, a centrifugal rotor having a separating chamber including a plurality of superimposed spaced frusto-conical discs forming separating spaces between said discs, individual radially extending vanes interposed between opposing faces of successive discs, each said vane extending from one opposed face to the other throughout substantially the entire radial extent of the opposed faces to form channels through which gas may flow radially inwardly within the spaces between successive discs during separation of non-gaseous constituents therefrom, a feed zone through which the gas to be purified is conveyed outwardly into said separating chamber, said feed zone having a plurality of impeller elements for imparting rotation to said gas to be purified, a peripheral wall surrounding said discs and spaced radially therefrom, a plurality of outwardly extending indentations in said peripheral wall forming pockets, said pockets having normally open holes for the discharge therefrom of precipitated impurities, and a discharge zone in the central portion of the rotor positioned inwardly of the inner circumferences of said discs, said discharge zone increasing progressively in cross-sectional area in the direction of flow of gas from the feed zone through said rotor, said discharge zone containing a plurality of radially extending vanes, and a non-rotating receiving member for receiving said gas directly from said discharge zone.

2. In a centrifugal separator for separating non-gaseous impurities from a gas, the combination comprising, a centrifugal rotor having a separating chamber including a plurality of superimposed spaced frusto-conical discs forming separating spaces between said discs, individual radially extending vanes interposed between opposing faces of successive discs, each said vane extending from one opposed face to the other throughout substantially the entire radial extent of the opposed faces to form channels through which gas may flow radially inwardly within the spaces between successive discs during separation of non-gaseous constituents therefrom, a feed zone through which the gas to be purified is conveyed outwardly into said separating chamber, said feed zone having a plurality of impeller elements for imparting rotation to said gas to be purified, a peripheral wall surrounding said discs and spaced radially therefrom, a plurality of outwardly extending indentations in said peripheral wall forming pockets, said pockets having normally open holes for the discharge therefrom of precipitated impurities, and a discharge zone in the central portion of the rotor positioned inwardly of the inner circumferences of said discs, said discharge zone increasing progressively in cross-sectional area in the direction of flow of gas from the feed zone through said rotor, said discharge zone containing a plurality of radially extending vanes, and a non-rotating receiving member for receiving said gas directly from said discharge zone.

5 wall forming pockets, said pockets having normally open holes for the discharge therefrom of precipitated impurities, a stationary wall surrounding the peripheral wall of said rotor, said stationary wall having a longitudinally extending slot therethrough communicating with a passage directed tangentially with respect to said rotor for directing impurities discharged from said rotor away from the zone of centrifugation under the inertia of discharge of said impurities from the rotor, and a discharge zone in the central portion of the rotor positioned inwardly of the inner circumferences of said discs, said discharge zone increasing progressively in cross-sectional area in the direction of flow of gas from the feed zone through said rotor, said discharge zone containing a plurality of radially extending vanes, and a non-rotating receiving member for receiving said gas directly from said discharge zone.

10 3. In a centrifugal separator for separating non-gaseous constituents from a gas, the combination comprising, a centrifugal rotor having a separating chamber containing a stack of superimposed spaced frusto-conical discs with separating spaces between said discs, vanes interposed between opposing faces of successive discs, said vanes forming channels through which gas may flow inwardly within the spaces between successive discs during separation of non-gaseous constituents therefrom, a feed zone for conveying feed gas outwardly of said discs into said separating chamber, said feed zone having a plurality of impeller elements for imparting rotation to said gas, a peripheral wall surrounding said discs and spaced radially therefrom, a plurality of small discharge outlets in said peripheral wall, said discharge outlets being distributed about said stack of discs for the discharge of separated non-gaseous constituents, a discharge zone in the central portion of the rotor positioned inwardly of the inner circumferences of said discs, said discharge zone increasing progressively in cross sectional area in the direction of flow of gas from the feed zone through said rotor, and a plurality of radially and axially extending vanes in said discharge zone.
